SLIDING HOOD

Hermann Lange, Erlenbach, Switzerland

Application November 26, 1935, Serial No. 51,656

2 Claims. (Cl. 296—137)

Sliding hoods are known in which hoops supporting the roofing are arranged, which are guided in guides along the roof aperture. The displacement of the end hoops can be effected by means of pull chains to which these hoops are rigidly connected. This rigid connection of the end hoops to the chains may, however, in the event of overstressing such as often occurs at the extremities of movement, lead to damage to the pulling mechanism and the bearing parts. Moreover, the rigid connection between the chains and end hoops makes fitting more difficult.

In constructions in which the chains and guiding elements are separate the appearance of the vehicle is impaired and separate projecting and easily deformable packing elements are necessary. In the case of assembled constructions wherein the chains are situated directly in the guide elements the accessibility for overcoming breakdowns, lubricating the chains and the like is rendered more difficult.

The present invention relates to a sliding hood by means of which these objections are overcome in a simple and reliable manner. This is attained by the fact that on longitudinal bars U-section guides and parallel to and at the same height as these bars the endless pull chains are arranged, the upper part of each pull chain being exposed at the top and situated between its guide and the middle of the end face of the hoops, whereas the lower parts of the chains are accommodated in guide channels provided in the bars and closed by inverted T-section irons arranged on the longitudinal sides of the roof aperture, which irons project above the upper chain part and serve for supporting and guiding the hoops, noses being provided on anchor-pieces on the end hoops which noses engage from above at any desired point in the links of the chains.

An embodiment of the invention is illustrated by way of example on the accompanying drawings in which:—

Fig. 1 shows the sliding hood in top plan view without covering material, and in the open position, the hoops being pushed together towards the middle of the hood.

Fig. 1a is a similar view showing the hood in closed position, the steel spring band being partly broken away.

Fig. 2 is a partial side elevation of the sliding hood in longitudinal section viewed from the front partly open.

Fig. 2a is a similar view showing the hood in closed position.

Fig. 3 shows in cross section a portion of the

sliding hood within the range of the front end hoop.

Fig. 4 shows the front portion of the hood in longitudinal section on line I—I of Fig. 5.

Fig. 5 is a top plan view of Fig. 4.

Fig. 6 shows the rear portion of the hood in longitudinal section on line II—II of Fig. 7 and

Fig. 7 is a top plan view of Fig. 6.

The solid roof portion 1 has a rectangular aperture 2 adapted to be covered by the sliding hood and to be covered partly or almost completely by a shiftable hood portion. The shiftable hood consists of a tarpaulin roof 3 and an inner lining 4 stretched over hoops 5 shiftable in the longitudinal direction of the roof and fixed on them so that the hoops are between cover and lining and fold the hood in upwardly projecting folds when the sliding hood is pushed together. Between every two hoops 5 the tarpaulin cover and the lining are connected the one with the other by rods 6 (Fig. 2) which, during the pushing together of the hood, move upwards together with the folds formed by the cover. The ends of the hoops 5 are slightly bent downwards and adapt themselves to the shape of the roof part 1. In order that the tarpaulin cover be folded into uniform upwardly directed folds, the ends of the hoops (Fig. 3) are connected on their lower sides by bands 7 with steel spring inserts, said bands being uniformly bulged upward together with the tarpaulin cover during the pushing together of the hoops 5. Guide grooves 8 having inwardly bent edges serve to guide the hoops 5 and are fixed on the longitudinal bars 9 on the side edges of the rectangular aperture 2. Guide pieces 10 made of bend-leather fixed on the ends of the hoops 5 engage with these guide grooves 8. The side bars 9 have each a projection 11 on the upper side designed to prevent access of rain water to the guide grooves 8. This projection 11 is also provided on the transverse bars 12 of the solid roof part 1 at the front and rear edge of the aperture 2 so that this projection extends all round this aperture. The extreme hoop 5' at the front end and the extreme hoop 5'' at the rear end have each projecting rigid covering strips 13 (Figs. 1, 2, and 6) which same as the ends of the hoops 5, 5', 5'' engage over the projection 11 and are slightly curved downwards so that they bear against the rigid roof part 1. To ensure a good and absolutely tight bearing of these covering strips 13 on to the roof 1 the ends 8' of the guide grooves 8 (Figs. 4 and 5) are slightly curved downwards so that, when the extreme hoops 5', 5'' respectively strike against the trans-

50
55

verse bars 12, they are turned in such a manner that the covering strips 13 are pressed tightly against the solid roof 1. For completing the hermetical closure an overlapping strip 14 (Figs. 4 to 7) is fixed on the transverse bars 12 and has a rubber insert 15. If the slideable hood is closed, the covering strips 13 are pressed against the rubber insert 15 and at the same time partly covered by the strips 14 so that even when the car travels rapidly no rain can penetrate under the hood.

For motor cars a mechanical actuating device for opening and closing the shiftable hood is arranged so that it can be actuated from the driver's seat. With this object in view the side bars 9 in the aperture have each in the inner side a longitudinal groove 16, 17 respectively in which on each side of the aperture 2 an endless chain 18 extends. Sprocket wheels 19, 20 are arranged in a recess between the side bars 12 and the solid roof 1. The endless chains 12 are stretched over these sprocket wheels. The front sprocket wheels 19 are keyed each on one end of an axle 21 journaled in ball bearings 22 of a bracket 23 (Fig. 5). These brackets are fixed by means of screws on the front transverse bar 12 and the solid roof portion 1. The axle can be turned for instance by means of cranks and driving chain not shown in the drawings from the driver's seat so that the endless chains 18 are moved. The hoop 5' at the front end of the hood moves with the endless chains as it has at its ends anchoring pieces 24 which by a downwardly directed projection 25 engage in the upper side of the endless chains 18. The rear extreme hoop 5'' is not in engagement with the endless chains 18. This end hoop 5'' can be shifted by hand if the slideable hood has to be opened from the rear to the front.

The rear sprocket wheels 20 are mounted in brackets 26 shiftable in the longitudinal direction in order to permit a restretching of the endless chains 18. These brackets 26 are shiftable mounted on a plate 28 having longitudinal slots 27 and fixed on the lower side of the rear transverse bar 12 and on the roof part 1 above a recess. Screw bolts 29 at the foot of the bracket 26 extend downwards through these longitudinal slots 26. On the lower ends of the screw bolts 29 underneat the plate 28 nuts 30 are screwed for securely mounting the brackets on the plate 28. For adjusting the brackets 26 screw spindles 32 one for each bracket are mounted in bearings 39 of the rear transverse bar 12, said spindles bearing against the bracket 26 and having each a square end for a socket wrench. If the chains 18 have to be restretched the nuts 30 have to be loosened and the supports to be shifted by turning the screw spindle 32 by means of the socket wrench until the chains are well stretched.

Lubricating sleeves 33 are inserted into the brackets 26 and have each a piston 34 controlled

by springs or adapted to be adjusted by hand for feeding lubricant or oil to the sprocket wheels 20 and to the chains 18.

The shiftable hood as described can be pushed from the driver's seat with the aid of the mechanical actuating device from the front end to the rear end or only partly so that the front portion of the rectangular aperture 2 is opened. If the shiftable hood is only partly opened, the rear portion of the hood may be pushed forward as far as desired. If the rear portion is partly pushed forward it is no longer necessary to actuate the shiftable hood by hand as the shiftable hood can first be pushed to the rear by means of the mechanical actuating device and then by actuating this mechanical device in opposite direction pulled to the front end so that it closes the aperture. The shiftable hood may be closed in a similar manner also if it has been pushed by hand completely towards the front end.

The rear extreme hoop 5'' might be connected with the endless chains instead of the front extreme hoop so that in this case the shiftable hood must be opened in inverse direction, i. e. from the rear to the front mechanically and also closed.

I claim:—

1. A sliding hood, comprising in combination hoops, longitudinal bars one on each side of said hoops and each having a guide channel on its inner side, U-section guides on the upper side of each of said bars, endless pull link chains mounted on each of said bars and extending parallel to said guides, the upper part of each chain being exposed on its upper side and situated at the same height as the adjacent guide and guided between this guide and the middle of the end face of said hoops, and the lower part of each chain being accommodated in a guide channel in its bar, inverted T-section irons arranged one on the inner side of each of said bars, the upright arms of said irons forming the outer wall of said guide channels and extending above the upper chain part and the inwardly projecting horizontal arm T-section forming a supporting guide for said hoops, and anchor pieces at the ends of one of the end hoops loosely engaging from above in the upper part of said chains at any desired link.

2. In a vehicle top formed with an opening, longitudinal members disposed at each side of said opening, each of said members being formed with a channel open at the top, an endless link chain disposed in each of said channels, the upper side of each chain being exposed through the open top of the channel, a plurality of transverse bows extending across said opening and slidably supported at their ends, flexible covering material secured to said bows, and means secured to one of the end bows and extending downwardly into links of said chains for releasably engaging said chains.

HERMANN LANGE.
